UNITED STATES PATENT OFFICE.

ABRAHAM T. H. BROWER, OF CHICAGO, ILLINOIS.

PRINTING-PRESS.

1,218,049.

Specification of Letters Patent.

Patented Mar. 6, 1917.

Application filed November 23, 1912. Serial No. 733,165.

To all whom it may concern:

Be it known that I, ABRAHAM T. H. BROWER, a citizen of the United States, and a resident of Chicago, county of Cook, and 5 State of Illinois, have invented certain new and useful Improvements in Printing-Presses, of which the following is a full, clear, and exact description.

The invention relates to printing presses 10 and more particularly to proof presses employing a reciprocating type bed and a paper carrying cylinder geared to the bed to effect the forward printing and returning movements of the bed as the cylinder 15 is rotated in opposite directions. The invention seeks to provide improved means for mounting the cylinder and for raising and lowering the same to and from the bed, so that the tympan will not contact with the 20 type surface upon the return movements of the bed and cylinder. The invention also seeks to provide improved means for arresting forward and return movements of the bed and cylinder without shock.

25 The invention consists in the features of improvement hereinafter set forth, illustrated in the preferred form in the accompanying drawings and more particularly pointed out in the appended claims.

30 In the drawings, Figure 1 is a side elevation of the improved press with one end of the frame and the lower portion of the base broken away, and with parts shown in section on the line 1-1 of Fig. 2. Fig. 2 is 35 a cross-section on the line 2-2 of Fig. 1. Fig. 3 is a partial cross-section on the line 3-3 of Fig. 1. Figs. 4, 5 and 6 are detail sections on the lines 4-4, 5-5 and 6-6, respectively of Fig. 2. Figs. 7 and 8 are 40 detail sections on the lines 7-7 and 8-8, respectively, of Fig. 2.

The horizontal frame 10 of the press is mounted on and is securely bolted to a suitable supporting standard or base 11. 45 These parts are formed of cast iron and the frame 10 is strengthened at intervals by transverse webs 12. At its upper portion the frame 10 is provided with guides 13 for the reciprocating type bed 14. The 50 latter is provided on its under side with longitudinally extending guide ribs 15 near its edges and with a central, longitudinal bearing rib 16, and also with transverse strengthening ribs 17. The ribs 15 and portions 55 of the frame are provided with guide grooves 18 which form race-ways for

two sets of bearing balls 19. Each set of bearing balls is held in proper position by a spacer bar 20 which is provided with openings for the individual balls and which is 60 arranged to slide upon the upper surfaces of the guide 13 on opposite sides of the groove 18 therein. The central portions of the guide grooves, as shown most clearly in Figs. 2 and 3, are cylindrical and are of the 65 same radius as the bearing balls 19. These cylindrical central portions of the grooves preferably extend through arcs of about 90° and the flaring side portions of the grooves are tangent to the central cylindrical portions thereof and to the bearing balls. 70

The ends of the spacer bars 20 are provided with stop blocks 21 which, at the ends of the movement of the bed, are arranged 75 to engage stop pieces 22 (see Fig. 1) fixed to the ends of the frame 10, so that the sets of bearing balls are maintained in proper position relatively to the reciprocating type bed. Preferably, the stop pieces 22 are 80 covered with raw hide, leather or the like.

To relieve the ball bearings in part from the pressure of the cylinder upon the bed, the central bearing rib 16 of the latter is arranged to engage a supporting wheel 23. 85 This wheel is mounted upon a short cross-shaft 24 that is journaled at its ends in the upright side portions of a bracket 25. This bracket is bolted to the upper portion of the base 11 between a pair of lugs 26 thereon. Shims 27 are interposed between the upper part of the base and the bracket 25 to take up any play between the guiding and supporting wheel 23 and the longitudinal 90 rib 16 of the bed. 95

The supporting and guiding wheel is arranged in vertical alinement with the axis of the cylinder 28 which is supported above the bed by a pair of heavy brackets 29. The lower portions of the cylinder brackets overlap the outer faces of the frame 10 and are firmly secured thereto by upper and lower sets of bolts 30. Preferably, as shown in Fig. 2, the cylinder brackets are provided with lips 29' which overlap the upper and lower edges of the frame 10. The ends of the cast iron cylinder 28 are provided with hubs 28' (see Figs. 3 and 5) which are keyed to a shaft 31. Each end of the shaft is journaled in a bush or bearing 32 and these bearings are arranged between the upper ends of the cylinder brackets and cap 100 105 110

pieces 33 which are secured to the brackets by bolts 34. The projecting ends of the shaft are provided with hand wheels 35, so that the cylinder may be rotated from either 5 side of the press.

The surface of the cylinder is recessed in the usual manner throughout the greater portion of its length to receive the tympan and at its ends is provided with bearing 10 flanges 36 which engage the bearers 37 fixed in the usual manner to the sides of the type bed. A gear wheel 38 is fixed to one end of the cylinder by screws 39 and meshes with a rack 40 fixed to one of the side edges 15 of the bed to thereby effect the forward and back movements of the latter as the cylinder is rotated in opposite directions. The cylinder is provided at its opposite end and adjacent its periphery with a laterally projecting stud 41 which is arranged to cooperate with a reciprocating or oscillating stop device on the frame of the machine to limit the movements of the cylinder and the bed. Preferably, the stud 41 is provided 20 with an anti-friction roller 42 which, at the opposite ends of the movement of the cylinder, is arranged to engage with one or the other of two notches or seats 43 formed in a segmental oscillating stop device 44. This 25 stop device is pivotally mounted on the inner face of the left hand cylinder bracket by a stud 45. A spring 46 is coiled about the hub of the stop device 44. One end of the spring is connected to the central portion 30 of the stop device and its other end is arranged between a pair of lugs 47 formed upon the inner face of the cylinder bracket. Beneath the stop device, the cylinder bracket 35 is provided with inwardly projecting abutments or ledges 48 which are covered with a strip 49 of rawhide, leather or the like and against which the ends of the stop device strike when it is shifted in one or the other direction by the engagement of the 40 cylinder stop roller therewith. When the cylinder is shifted in forward direction (indicated by the arrow in Fig. 7), the stop roller 42 thereon passes out of one of the seats 43 and the spring 46 then holds the 45 stop device 44 in central position, so that at the end of the forward movement, the stop roller engages the other notch or seat 43 and shifts the stop device until its movement is arrested by its engagement with the 50 rawhide strip covering one of the abutments 48. The stop device thus serves to 55 yieldingly arrest the forward movement of the bed and cylinder without shock or jar and in a similar manner arrests the return movement of these parts.

The cylinder shaft bearings 32 are provided with eccentric portions 50 (see Figs. 1, 3, 7 and 8) which are free to oscillate in suitable seats to thereby lower and raise 60 the cylinder upon the forward and return

movements of the bed. Preferably, these eccentrics are fitted within outer eccentrics 51 and the latter in turn are arranged in seats formed in the upper ends of the brackets 29 and in the bracket cap pieces 33. The 65 outer eccentrics are shifted only when it is desired to adjust the cylinder to bring its tympan surface and flanges 36 in proper relation to the type bed and the bearers 37 thereon. For convenience in adjusting the 70 eccentrics 51, they are provided with a series of radial holes 52. These outer eccentrics can only be shifted by removing the cap pieces 33 and, once they are properly set, they are securely clamped in place and 75 so held against movement by the cap pieces which, in turn, are held in position by the bolts 34. Each of the inner eccentrics or 80 shaft bearings is provided with a flange 53 which overlaps the inner face of the outer eccentric 51 and also abuts against the inner faces of the cylinder bracket 29 and the bracket cap 33. A plate 54 similar in size to the flange 53 overlaps the outer faces 85 of these parts and is connected to the main body of the inner eccentric bearing by screws 55 to thereby hold the cylinder, cylinder shaft bearings and outer adjusting or take-up eccentrics in position.

The inner eccentric bearings 50 are free 90 to oscillate within their seats in the outer adjusting eccentrics and, to effect such oscillation, are provided with crank arms 56 and 57. The crank arm 56 (see Figs. 2 and 8) on the left hand cylinder bearing 100 is arranged outside of the adjacent cylinder bracket 29 and is formed in piece with the plate 54 which is fastened to the adjacent bearing. The crank arm 57 is arranged inside the right hand bracket 29 and is formed 105 in piece with the main body of the right hand bearing 32 (see Figs. 1 and 4). The ends of these crank arms are forked and are connected to the upper ends of a pair of links 58. The lower ends of these links 110 are connected to the forked ends of a pair of shift levers 59 and 60. These shifters or levers extend beneath the cylinder bearings and are mounted, at their forward ends, upon a common transverse rock shaft 61 115 that is journaled in the cylinder brackets 29. The shift levers 59 and 60 are both keyed to the shaft 61 so that they are moved together to thereby oscillate the eccentric shaft bearings 50 to raise and lower the 120 cylinder.

The shift of the levers 59 and 60 is controlled by a double-path cam mounted on one end of the cylinder. Preferably, this cam is formed in piece with the gear 38, the 125 outer face of which is provided with inner and outer cam grooves 62 and 63 which are separated by a rib 64 except at the portion of the cam which is lowermost when the bed and cylinder are at the ends of their move- 130

ment. At this portion, the ends of the outer cam groove 63 are curved inwardly and merge into the inner cam groove 62. These cam grooves coöperate with a stud 65 on the 5 adjacent shift lever 60 and which stud is preferably provided with an anti-friction roller 66 extending within the grooves. One end of the inner groove 62 is normally closed by a gate 67 which is pivotally connected to the cam by a screw 68 and which is held in normal position by a V-shaped 10 spring 69 (see Figs. 1, 3 and 4). This spring is arranged in a recess in the inner face of the gate and its ends respectively engage the gate and the cam body. The tendency 15 of the arms of this V-shaped spring to spread apart holds the gate in the normal position shown in Fig. 1 and in full lines in Fig. 4. When the paper carrying cylinder 20 and type bed are in the initial position shown in the drawings, the roller 66 on the shift lever 60 is in the position shown and the cylinder is in its lowermost position with the flanges 36 thereof engaging the bearers 25 37 of the type bed. Upon the forward movement of the cylinder in the direction indicated by the arrows in Figs. 1, 4 and 8, the roller 66 on the shift lever enters the open end of the inner cam groove 62 and is maintained in this groove to hold the cylinder in 30 engagement with the type bed until the cylinder has completed a full revolution which constitutes this forward movement. As the cylinder approaches the end of its 35 forward movement, the roller engages the rear inclined edge of the gate 67 and swings it about its pivot against the tension of the spring 69, so that the roller can pass the gate and again occupy the position shown in 40 Figs. 1 and 4. On the reverse or return movement of the cylinder, the roller 66 engages the end of the gate and is guided thereby into the outer cam groove 63, so that the shift levers 59 and 60 are depressed and, 45 through the medium of the links 58, oscillate the eccentric shaft bearings 50, and thereby the cylinder is raised during the return movement of the bed and cylinder. At the end of the return revolution of the 50 cylinder, the roller 66 and the shift levers 59 and 60 controlled thereby are returned to the position shown and the cylinder is again lowered into engagement with the bed. In this way, the cylinder is held in lowered 55 position during the forward or printing stroke of the bed and cylinder and is automatically raised to clear the type surface on the return movement of these parts. The vertical shift of the cylinder effected by the 60 eccentrics 50 is slight, but is sufficient to raise the tympan on the cylinder clear of the type surface during the return movements of the cylinder and bed. This slight shift is not sufficient to disturb the proper mesh- 65 ing of the cylinder gear 38 with the bed rack

40. During the forward movement of the bed and cylinder, the center of the cylinder shaft 31 is vertically in line and below the centers of the eccentrics 50, so that the pressure of the type surface against the cylinder cannot tend to turn these eccentrics. Furthermore, these eccentrics do not have to be shifted to adjust the cylinder to take up any play between it and the bed, since any such adjustment is effected by means of the outer eccentrics 51. As stated, the outer eccentrics when once adjusted, are clamped against movement by the bracket caps 33. 70 75

The cylinder is provided, as usual, on one side with an opening and one of the edge 80 walls of this opening has a series of pins 70 which coöperate with a series of clamps 71 for securing one end of the tympan to the cylinder. The tympan clamps are mounted upon a cross-shaft or rod 72 arranged with 85 in the cylinder and journaled in the ends thereof. At one end and outside of the cylinder, this shaft is provided with an arm or lever 73 which normally engages a lug 74 on the end of the cylinder to hold the tympan clamps in position. The arm 73 is formed of spring steel, so that it may be shifted laterally into and out of engagement with the lug 74 to release and secure the tympan. The opposite ends of the blankets 90 forming the tympan pass around a pair of toothed reel rods 75 journaled within the cylinder adjacent the opposite edge of the opening thereof. These rods are provided with square shanks 76 (see Fig. 7) which 95 project beyond one end of the cylinder for receiving suitable tools by which the blankets may be drawn tightly around the cylinder. Ratchets 78 and coöoperating spring-held pawls 79 prevent the unwinding movement 100 of the reel rods. 105

A series of grippers 80 for holding the leading edge of the paper against the tympan are mounted upon a rod 81 which is journaled in the ends of the cylinder and is arranged, as shown, near the edge of the cylinder opening. A crank arm 82 on one end of the rod or shaft 81 is connected to the hooked end of a sliding bolt 83. The latter is arranged to slide and also oscillate to a slight extent through a stud 84 fixed to the inner face of the left hand end of the cylinder. A spring 85, coiled about this rod, extends between the washers 86 that abut respectively against the stud 84 and 115 against a nut 87 fixed to the end of the bolt, so that the tension of the spring is exerted to hold the grippers 80 against the leading edge of the tympan. The left hand end of the gripper shaft or rod 81 outside of the 120 end of the cylinder is provided with a handle 88 by which the grippers may be oscillated and shifted to disengaged position. In this disengaged position, the outer curved end of the spring bolt 83 hooks over the 125 130

shaft or rod 81 so that the spring 85 then acts to hold the grippers away from the cylinder. The grippers are only shifted to this extreme disengaged position when it is desired to adjust the tympan, but inasmuch as the gripper spring is thus arranged to shift on opposite sides of a central position, it will act to yieldingly hold the grippers both in normal and in disengaged position.

10 Means is provided for shifting the grippers slightly to release the leading edge of the paper, and is so arranged that the grippers may be released by hand or automatically. A shaft 89 extends in front of the cylinder and is journaled at its ends in the cylinder brackets 29. An eccentric cam 90 (see Figs. 2, 5 and 8) is fixed to the left hand end of this shaft. The edge of this eccentric cam engages the outer curved edge portion at the upper end of an intervening arm or trip device 91 and which arm is pivotally mounted at its lower end on a cross-rod 92 extending between the cylinder brackets. The intervening arm or releasing trip 25 is provided at its upper end and on its inner edge with an inclined cam face 93 which is arranged to coöperate with a roller 94 on the end of an arm 95 which is fixed to the left hand end of the gripper shaft or rod 81.

30 The shaft 89 is provided at the left hand end of the machine with a handle 96 (see Figs. 2 and 8) and at the opposite end of the machine (see Figs. 1 and 2) it is provided with a handle 97, having an enlarged notched hub 98. A dog 99 pivoted on the right hand end of the rod 92 is pressed toward the notched hub 98 by a spring 100, which extends between the dog and the lug 100' on the outer face of the right hand cylinder bracket. The movement of the eccentric cam 90 and intervening arm 91 is limited in one direction by the engagement of the curved outer end of the handle 97 with the edge of the cylinder bracket 29.

45 In the opposite direction, the movement of these parts is limited by the engagement of a toe-piece 101 on the pivoted end of the intervening arm or releasing trip 91 with a projecting lug 102 on the inner face of the 50 left hand cylinder bracket.

With the low part of the eccentric cam 90 in engagement with the intervening arm or releasing trip, the roller 94 will clear the inclined cam face 93 at the upper end of the arm, so that the grippers will not be automatically released, but, in the initial position of the cylinder, the shaft 89 can be rotated from either side of the machine by means of either of the handles 96 or 97 and 60 the upper end of the arm 91 forced against the roller 94 to rock the gripper shaft 81 against the tension of the spring 85 and thereby release the grippers. The paper may then be placed in position on the cylinder with its front edge against the guides

provided therefor and then, by releasing the eccentric cam 90, the spring 85 will shift the grippers to engage the paper.

If desired, the eccentric cam 90 can be held in shifted position by means of the dog 70 99 on the right hand side of the machine, so that the grippers will be automatically released at the end of the forward movement of the cylinder and will be automatically returned to position to grip the paper after 75 the cylinder is moved forward to disengage the roller 94 from the inclined cam face 93 of the intervening arm or trip device 91. The hub 98 with which the dog 99 coöperates, is provided with a number of notches 80 so that the dog serves to hold the cam 90 and the trip arm in any one of a number of different positions. In the position shown the grippers are released by hand. In the other positions the grippers are automatically released and restored at different points. The end of the dog and the notches of the hub are provided with oppositely inclined faces so that the shaft 89 and cam 90 can be turned or adjusted as desired by 90 means of the handles 96 and 97. It should be noted that handles are provided on opposite ends of the cylinder shaft 31 and of the gripper controlling shaft 89, so that the press can be readily operated from either 95 side.

The front guides for the leading edge of the paper comprise a series of U-shaped fingers 103 which are mounted upon a rod 104 and extend around the edge of the cylinder opening. This rod is journaled in the ends of the cylinder and at its left hand end has an arm 105 fixed thereto. A cushion spring 106 extends between the end of this arm and the end of an arm 107 which is loosely 105 mounted on the rod 104 and is pressed by the spring 106 against the outer cylinder wall. Preferably, as shown, the front guide fingers 103 are provided at points in line with the surface of the tympan with shoulders 103' to aid in accurately positioning the paper on the cylinder.

It should be noted that the outer face of the cylinder adjacent the edge of the cylinder opening is cut away, so that the paper grippers lie within the periphery of the cylinder bearing flanges 36 and will, therefore, clear the surface of the type and chase upon the bed 14, and means are provided for shifting the front guides 103 to also clear all 120 portions of the type surface. For this purpose, the front guide rod or shaft 104 is provided on its left hand end with an arm 108 (see Fig. 7) having a roller 109 on its end. As the cylinder is rotated, and as the guide fingers approach the type surface, the roller 109 engages a fixed curved cam ledge 110 which is secured to the inner face of the left hand cylinder bracket by studs 111 (see Figs. 2 and 7). In this manner, the front 130

guide fingers are automatically withdrawn into the cylinder to clear the type and all portions of any type-high chase on the bed during both the forward and back movement of the bed and cylinder.

5 A sleeve 112 fits over the rock shaft 89 and interlocks with a part 112' on the right hand cylinder bracket so that it is held against movement. The shaft 89, however, 10 is free to rock within this sleeve. A series of brackets or collars 113 are fixed to the sleeve 112 and a series of sheet guiding bands 114 are fixed at the upper ends to these brackets or collars. Intermediate 15 their ends, the sheet guiding bands are provided with doubled, offset portions 115 which are riveted together and the outer looped ends of which encircle the transverse rod 92.

20 In operation, the paper sheet is placed on the cylinder with its leading edge engaging the guide fingers 103 and the shoulders 103' thereof, so that it will be engaged by the grippers 80. If necessary, the grippers 80 25 are shifted by means of the cam 90 on the shaft 89 and the intermediate arm 91, as described, before the edge of the paper is engaged with the guide fingers. The grippers may then be engaged with the forward edge 30 of the paper to hold it in place. As above described, the intermediate arm 91 may be held in such position by the cam 90 that it will automatically release the fingers. As above described, the intermediate arm 91 35 may be held in such position that in the normal position of the cylinder, the grippers will be held released, but will engage the forward edge of the paper as soon as the initial movement of the cylinder disengages 40 the roller 94 from the inclined cam face 93 of the arm. The cylinder is then rotated by one of the handles 35 to shift the bed and carry the paper on the cylinder into engagement with the type on the bed. During 45 this forward movement, as previously described, the roller 66 passes through the inner grooves 62 of the double-path cam on the cylinder, so that the latter is maintained in engagement with the type bed until it has 50 completed a full revolution in forward direction. At the end of a single revolution of the cylinder in forward direction, the grippers 80 are released, either by hand or automatically, as described, and the paper is 55 removed from the cylinder. The cylinder is then rotated in the opposite direction to initial position. During this movement, the roller 66 is guided by the gate 67 into the outer groove of the double-path cam and the 60 cylinder is raised by oscillating the eccentric shaft bearings 50 through the medium of the levers 59 and 60 and links 58. The movement of the cylinder and bed in opposite directions is limited by a stop device 44, as already described.

It is obvious that numerous changes may be made in the details set forth without departure from the essentials of the invention as defined in the claims.

I claim as my invention:

1. In a printing press, the combination with the frame, cylinder and reciprocating type bed, of eccentric bearings for said cylinder, shifters connected to said bearings to oscillate the same to raise and lower the cylinder, and a cam on said cylinder for operating said shifters at the ends of the movements of said bed, said cam coöperating with said shifters to hold the cylinder in raised position during the return movement of the bed.

2. In a printing press, the combination with the frame, cylinder and reciprocating type bed, of eccentric bearings for said cylinder, shifters for oscillating said bearings to raise the cylinder upon the return movement of the bed, and a double-path cam on said cylinder for operating said shifters, said cam having a controlling gate at the junction of the paths thereof.

3. In a printing press, the combination with the frame, cylinder and reciprocating type bed, of eccentric bearings for said cylinder, a pair of shift levers connected to said eccentric bearings, and a cam on said cylinder for operating said levers to thereby oscillate said bearings to raise the cylinder at the end of the forward movement and lower said cylinder at the end of the back movement.

4. In a printing press, the combination with the frame, cylinder and reciprocating type bed, of eccentric bearings for said cylinder, a pair of shift levers connected together and to said eccentric bearings, and a double path cam on said cylinder for operating said levers, said cam having a controlling gate at the junction of the paths thereof.

5. In a printing press, the combination with the frame, of a type bed thereon, a cylinder geared to said bed to reciprocate the same as said cylinder is rotated in opposite directions, eccentric bearings for said cylinder, a double-path cam connected to rotate in opposite directions with said cylinder, and means operated by said cam for oscillating said bearings to lower and raise the cylinder at the ends of its movement.

6. In a printing press, the combination with the frame, of a type bed thereon, a cylinder geared to said bed to reciprocate the same as said cylinder is rotated in opposite directions, eccentric bearings for said cylinder, a double-path cam connected to rotate in opposite directions with said cylinder, said cam having a controlling gate at the junction of the paths thereof, and lever mechanism operated by said cam for oscillating said bearings to lower the cylinder

- upon the return movement respectively of the bed.
7. In a printing press, the combination with the frame, of a type bed thereon, a cylinder geared to said bed to reciprocate the same as said cylinder is rotated in opposite directions, a double-path cam on one end of said cylinder having a controlling gate at the junction of the paths thereof, and lever mechanism operated by said cam for raising and lowering said cylinder at the ends of its movement.
8. In a printing press, the combination with the frame, of a type bed thereon, a cylinder geared to said bed to reciprocate the same as said cylinder is rotated in opposite directions, eccentric bearings for said cylinder having crank arms, a pair of shift levers mounted on a common rock shaft and connected to said crank arms, and a double path cam on one end of said cylinder for operating said shift levers, said cam having a pivoted controlling gate at the junction of the paths thereof.
9. In a printing press, the combination with the frame, of a type bed thereon, a cylinder geared to said bed to reciprocate the same as said cylinder is rotated in opposite directions, eccentric bearings for said cylinder having crank arms, a pair of shift levers mounted on a common rock shaft and connected to said crank arms, and a cam on one end of said cylinder having inner and outer cam grooves, one of said levers having a stud engaging said cam grooves, and said cam having a pivoted spring-held gate at the junction of said grooves for guiding said stud into the outer groove upon the reverse movement of said bed and cylinder.
10. In a printing press, the combination of a frame, a cylinder and a reciprocating type bed, of cylinder supporting brackets secured to said frame, outer adjusting eccentrics for effecting the pressure regulation seated in said brackets, inner oscillating eccentric bearings for said cylinder seated in said outer adjusting eccentrics, shift lever mechanism connected to said inner eccentric bearings for oscillating the same to raise and lower the cylinder at the ends of the reciprocations of said bed and for holding the same in raised position during the movement of the bed, and means for clamping said outer adjusting eccentrics to said brackets to hold the same against movement, substantially as described.
11. In a printing press, the combination with the frame, of a type bed, a cylinder geared to said bed to reciprocate the same as said cylinder is rotated in opposite directions, brackets fixed to said frame, adjusting eccentrics seated on said brackets, caps for holding said eccentrics in position, eccentric bearings for said cylinder seated in said adjusting eccentrics, shift levers connected to said bearings for oscillating the same, and a cam on one end of said cylinder for operating said shift levers.
12. In a printing press, the combination with the frame, of a type bed, a cylinder geared to said bed to reciprocate the same as said cylinder is rotated in opposite directions, a stop lug on one end of said cylinder, an oscillating, centrally spring-held stop device on said frame arranged to be engaged by said stop lug at the ends of the movements of said cylinder in opposite directions, and cushioned abutments on the frame for limiting the movement of said stop device.
13. In a printing press, the combination with the frame, of a type bed, a cylinder geared to said bed to reciprocate the same as said cylinder is rotated in opposite directions, cylinder brackets having lips overlapping the upper and lower edges of said frame, upper and lower sets of bolts securing said brackets to said frame, a shaft whereon said cylinder is mounted journaled in said brackets, a hand wheel on said shaft, and means for limiting the forward and return movements of said bed and cylinder.

ABRAHAM T. H. BROWER.
